UNITED STATES PATENT OFFICE.

PERRY R. CHAMBERLEN, OF SEATTLE, WASHINGTON.

FIRELESS COOKER.

1,275,222.

Specification of Letters Patent. Patented Aug. 13, 1918.

Application filed April 5, 1917. Serial No. 159,896.

To all whom it may concern:

Be it known that I, PERRY R. CHAMBERLEN, a citizen of the United States, and resident of the city of Seattle, county of King, 5 and State of Washington, have invented certain new and useful Improvements in Fireless Cookers, of which the following is a specification.

My invention relates to fireless cookers 10 and consists of certain improvements in the construction thereof which will be herein-after described and then particularly pointed out in the claims.

In the accompanying drawings I have 15 shown my invention embodied in the forms of construction which are now most preferred by me.

Figures 1 and 2 are vertical sections taken 20 through the assembled device, the two showing slightly modified constructions in the base thereof.

The type of fireless cooker herein shown is one which employs an inclosing bell-shaped heat-insulating container, open at 25 the bottom, which is placed over the vessel containing the food to be cooked and which employs a base for the reception of both the vessel containing the food and the bottom of the inclosing bell. Upon this base a heat 30 radiating element may be placed, if desired, beneath the food being cooked.

The bell may be of any suitable construction and may be varied to suit desires and conditions. As herein shown, it consists of 35 two cylindrical drums placed one within the other and having the space between them filled with any suitable heat insulating material. The shape and size of this, as well as the manner of its construction, may be 40 varied as desired. The really essential feature is that it be of a bell-shape, that is, a chamber in which one end is lacking, and be of heat insulating or retaining construction. It should also, for convenience and 45 practical reasons, be of a unitary or non-separable character.

The base contains two parts, the outer member 2, which, in its general construction roughly resembles a pan having an upstanding peripheral or marginal flange 20, 21, and an inner member forming a false bottom 3. The outer member 2 has its sides or marginal flange composed of two upwardly extending sections 20 and 21, joined together 55 by a horizontally disposed section 22, which provides an inwardly projecting ledge at a

point between its upper and lower edges. The upper section 20 of the flange is of a diameter sufficient to accommodate the lower open end of the inclosing drum 1.

60

The false bottom 3 may be varied somewhat in construction. In principle, this contains a marginal, or peripheral, zone which is in raised position and which has supporting engagement with the lower end of the 65 drum, and a central area within this, which is depressed somewhat and which receives and holds in place the heating element 4 when such a member is used. This heating element, in the type of construction herein 70 shown, is in the form of a circular disk and may be made of any material found suitable. For this purpose, soap stone is found to be very desirable.

In the construction shown in Fig. 1 the 75 false bottom is provided with a downwardly extending peripheral flange 38, which engages with the outer member 2 of the base, to support the false bottom. This has the raised marginal zone 36, which is beneath 80 the lower edge of the inclosing bell or drum. The central portion of the false bottom is depressed to receive the heating disk 4.

As shown in both figures, the end surface 85 of the inclosing drum overlaps the ledge 22 of the outer pan, or base member, and the marginal zone 36 of the false bottom. The depth of the flange 38 may be made such that the lower end of the drum 1 is supported in part, at least, upon the marginal zone 90 of the false bottom, or upon the two combined.

In Fig. 2 I have shown the outer marginal zone of the false bottom as provided 95 with a slight circular depression forming a groove 32, this being preferably placed at such point that it comes immediately under the inner edge of the wall of the drum. The object of this depression is to catch and hold such moisture of condensation as may 100 be formed on the inner wall of this drum and thus serve to better seal the joint between the lower end of this drum and the surface of the false bottom.

The construction shown in Fig. 2 has the 105 outer base member, or pan, 2, constructed substantially as shown in Fig. 1. The false bottom differs slightly in construction by having its central portion depressed so as to form a ledge 37, upon which the heating 110 disk 4 rests.

While the outer pan, or base member 2,

and the false bottom, or inner member 3, may be secured permanently together, if desired, I prefer that they should be detachable, so that the corners and the narrow spaces between them may be readily accessible for cleaning.

An examination of the construction of the base shows that in all cases a dead air space is imposed between the heating member 4 and the exterior. Also, that there is a dead air space interposed between the central space, or that which is immediately below the heating member, 4, and the outer edge, the same consisting of the annular chamber 50. These dead air spaces act as insulation to prevent escape of the heat. In the construction shown in Fig. 2, two dead air spaces, 51 and 52, are shown between the bottom of the heating disk 4 and the exterior air, or the object upon which the cooker is supported.

The above construction is a thoroughly practical and economical one to manufacture and one which may be quickly and easily kept clean. The parts most likely to become dirtied are separable and lacking in crevices or sharp corners which are difficult to clean. It also provides efficient insulation to retain the heat.

30. What I claim as my invention is:

1. In a fireless cooker, in combination, a heat insulating bell, a bottom composed of an outer and an inner plate-like member, provided with engaging parts holding the bodies thereof separated and both having top surfaces extending about their peripheries and together providing supporting surfaces for the lower end of the bell.

2. In a fireless cooker, in combination, a heat insulating bell, a bottom and a false bottom having peripheral flanges extending respectively upwardly and downwardly, the flange of the false bottom fitting just within the flange of the bottom and the flange of the bottom having a ledge on a level with the adjacent portion of the upper surface of the false bottom, said ledge and the adjacent surface of the false bottom forming supporting surfaces for the bottom of the bell.

3. In a fireless cooker, in combination, a heat insulating bell, a pan-like bottom hav-

ing an inwardly extending ledge below the top of its peripheral flange, a false bottom supported within the bottom to maintain its body separated from and above the true bottom, said false bottom having a top surface extending about its periphery and together with said ledge of the true bottom forming bell supporting surfaces.

4. In a fireless cooker, in combination, a heat insulating bell, a base therefor comprising a pan-like bottom member adapted to receive the lower end of the bell within its upstanding marginal flange and a false bottom having a downwardly extending peripheral flange loosely fitting within said marginal flange and also having a depressed central area, and a raised marginal zone extending under and supporting the end of said bell.

5. In a fireless cooker, in combination, a heat insulating bell, a base therefor comprising a pan-like bottom member adapted to receive the lower end of the bell within its marginal flange and a false bottom loosely fitting within said flange and having a depending flange engaging the said bottom to form a dead air insulating space between the two, and also having a marginal zone raised above the main central area thereof, and extending under the edge of the bell.

6. In a fireless cooker, in combination, a base having an upstanding marginal flange, a substantially level ledge intermediate the upper and lower parts thereof, a removable false bottom having a marginal zone adapted for supporting engagement with the lower edge of an inverted bell, said zone having a trough-like depression or groove positioned to be covered by the inner part of the lower end of the bell when placed thereon, said false bottom being depressed just within said groove but being at a level which is above the corresponding part of the bottom, and a bell-like cover adapted to have its lower end rest upon the marginal zone of the false bottom, and the ledge of the bottom.

Signed at Seattle, Washington, this 30th day of March, 1917.

PERRY R. CHAMBERLEN.
